Frank J. Garvey
ATTORNEY.

UNITED STATES PATENT OFFICE

2,592,136

VALVE FOR FOUNTAIN STENCIL BRUSHES

Edward S. Garvey, Clayton, Mo.

Application July 22, 1949, Serial No. 106,149

3 Claims. (Cl. 251—137)

1

My invention relates to fountain applicators for dispensing stenciling fluid from a reservoir handle to a stenciling medium, and, more particularly to a finger pressure actuated valve for controlling the admission of predetermined amounts of fluid from the reservoir to the interior of the stenciling medium, and for positively stopping the flow of fluid when the pressure is removed.

The primary object of the invention consists in providing a fluid control valve including a packing element therefor that may be replaced by the user of the applicator, thus obviating the necessity of sending the applicator back to the factory for replacement of the packing, which is the present practice, thus avoiding inconvenience to the user of the applicator due to the time lost in having the packing factory replaced.

A further object of the invention consists in providing a fluid control valve that will positively prevent bleeding of fluid from the reservoir to the stenciling medium, thus preventing the control means from becoming fluid flooded and thereby avoiding fluid being transferred from around the control means to the fingers of the applicator user.

Another object of the invention consists in providing a fountain applicator that possesses the foregoing features, which is simple in construction and in use, inexpensive in cost of manufacture, and which embodies a minimum number of parts.

The above objects of the invention are achieved, and highly efficient results attained, as is evident from a consideration of the following description and claims and from the illustration of the invention in the drawings.

Other objects and advantages of the invention will be clearly apparent during the course of the following description.

In the accompanying drawings, forming a part of this application, and in which like numerals are employed to designate like parts throughout the same,

Fig. 1 is a longitudinal sectional view of a fountain applicator embodying the features of a preferred embodiment of the invention.

Fig. 2 is a top plan view of the fountain applicator.

Fig. 3 is a transverse sectional view taken through the valve containing head portion of the reservoir and handle.

Fig. 4 is a fragmentary view showing the fluid control means depressed to allow admission of

2

fluid from the reservoir handle to the interior of the stenciling brush.

Fig. 5 is a view of the fluid control means with the parts thereof shown in extended positions.

5 The fountain applicator herein disclosed is used more particularly as a stenciling brush, or marker.

In the drawings, wherein for the purpose of illustration, is shown a preferred embodiment of my invention, the reference numeral 10 designates a tubular body portion which is preferably, although not necessarily, circular in cross-section and serves both as a reservoir, or container for stenciling fluid, such as ink, and as a handle for the operator to grasp when using the device. The outer end of the body portion 10 is closed by means of a suitable closure member, or cap 11 which is detachably secured thereto so that the reservoir may be easily filled with the stenciling fluid designated 12. A suitable gasket 11' is carried within the cap to engage the end face of the body portion 10 to provide a leak proof joint therebetween. The cap 11 is provided with a suitable bail-like member 13 which is shown as hingedly connected to the cap so that the applicator may be hung, or suspended from a nail, hook or other suitable support when the applicator is not in use.

The tubular body portion 10 opposite the cap supporting end includes a head-like portion 14 having an end socket 15 for detachable connection with the head 16 of a suitable stenciling, or marking brush made from suitable bristles 17. The head 16 of the brush is provided with a central port 18 to feed fluid to the inside of the brush, and there is a washer-like gasket 19 disposed between the bottom of the socket 15 and the head 16 of the brush to provide a leak proof joint between the wall of the socket 15 and the wall of the brush head 16. The brush head 16 is shown as having screw-threaded connection with the wall of the socket 15.

40 The head-like portion 14 is provided with a transverse bore to provide a socket 20 open to one side of the head portion only, and the head portion 14 is also provided in the wall of the transverse socket 20 with opposed ports 21 and

45 22 centrally of the longitudinal axis of the reservoir and handle portion 10, as clearly shown in Figs. 1 and 3. The port 21 is designed to carry fluid from the reservoir to a fluid control valve, later described, and after passing through the valve, the port 22 delivers the fluid to the brush head port 18 to be delivered to the interior of the stenciling brush, or marker, as is clearly apparent from Figs. 1 and 4.

50 The fluid control valve above referred to and

its parts illustrated in extended positions in Fig. 5, consists of a cylindrical valve body 23 open at both ends and provided at its one end with a flange 24. The valve body 23 has a press fit with the transverse bore, or socket 20 so as to lie between the aligned fluid ports 21 and 22, as clearly shown in Fig. 1. The flange 24 lies in a recess 25 in the head portion 14 surrounding the open end of the transverse bore, or socket 20. The valve body 23 is sealed within the bore, or socket 20, thus preventing fluid leakage between the head 14 and the valve body 23.

The end of the valve body 23 opposite the flange 24 is provided with an interior truncated cone shaped valve seat 26 and a wall recess 27 adapted to receive a pin 28 carried by a cone shaped valve member 29 adapted to normally engage the valve seat 26 so as to prevent rotation of the valve member 29 relative to the valve body 23 yet allow limited longitudinal sliding movement of the valve member 29 when it is desired to open the valve, as shown in Fig. 4 from its closed position, as shown in Fig. 1.

The interior wall of the valve body 23 is also provided with a truncated cone shaped packing seat 30 adjacent and opposed to the valve seat 26 to accommodate the seating of a suitable packing member 31 having a central opening 32 to receive the passage of a valve stem 33 which is screw-threaded, or otherwise detachably connected at its inner end with the inner end of the valve member 29 so that the valve members may be disconnected to replace a worn packing member 31. Both seats 26 and 30 are arranged intermediate the ends of the valve body 23. The valve stem 33 is provided at its outer end with a head 34 having a sliding fit with the inner wall of the valve body 23 and a portion of which head normally projects beyond the flanged end of the valve body so as to be actuated by a finger of the operator of the fountain applicator.

There is a suitable coiled spring 35 disposed between a washer 36 which engages the packing member 31 and the head 34 of the valve stem and the spring encircles the valve so as to exert pressure against the packing member 31 and against the head 34 of the valve stem to move the valve member to closed position when finger pressure is removed from the head 34 of the valve stem 33.

The valve body 23 is provided in the valve seat wall thereof with opposed fluid ports 37 and 38 which register with the fluid ports 21 and 22, respectively, so that fluid may be delivered from port 21 to the port 22 and then to port 18 to feed the brush bristles 17, when the valve stem has been forced inwardly by finger pressure on the projection head portion 34 of the valve stem. When the cone shaped valve member 29 has been moved away from its cone shaped valve seat 26 within the valve body, there will be provided an annular fluid passage 39 around the smaller end of the valve member 29 which communicates with the valve body ports 37 and 38, thus allowing controlled amounts of fluid to be delivered from the fluid reservoir to the interior of the stenciling brush, or marker, as will be clearly apparent from Fig. 4 of the drawing. When finger pressure is removed from the valve stem head 34, the spring 35 will close the valve and stop the flow of fluid from the reservoir to the interior of the brush, as will be apparent from Fig. 1.

The outer face of the valve stem head 34 is provided with a screw driver slot 40 so that with

the aid of a screw driver, the operator may disconnect the valve stem 33 from the cone shaped valve member 29 and remove the valve stem 33 and spring 35 from within the valve body 23.

5 After such removal of parts, the washer 36 and a worn packing member 31 may be fished out of the valve body 23 and a new packing member 31 placed within the valve body 23, thus obviating the necessity of having to send the applicator back to the factory for the mere replacement of a worn packing member 31. After a new packing 10 member 31 has been positioned within the valve body 23, the washer 36 and spring 35 are placed back in position and the valve stem is then screw-threadedly connected with the cone shaped valve member by means of a screw driver. It is clearly 15 apparent that the cone shaped valve member 29 cannot rotate or turn in the valve body when disconnecting the valve stem therefrom, or connecting it therewith, due to the pin and recess connection between the cone shaped valve member 29 and the valve body 23.

The many advantages of the herein described invention will readily suggest themselves to those skilled in the art to which it appertains.

25 It is to be understood that the form of my invention, herewith shown and described, is to be taken as a preferred example of the same, and that various changes in the shape, size, materials and arrangement of the parts may be resorted to without departing from the spirit of my invention, or the scope of the subjoined claims.

Having thus described my invention, I claim:

1. In a fountain applicator valve, a valve body 35 having opposed internal cone shaped seats intermediate the ends of the body, the wall of one of the seats having opposed ports, and further having a recess at the free end of the ported wall, a cone shaped valve member acting against the ported seat, said valve member having a pin engageable in said wall recess to prevent rotation of the valve member, a tubular packing acting against the other seat, a washer acting against the packing, a valve stem passing through the washer and packing and detachably connected at one end with the small end of the valve member, a head having a screw driver slot on the opposite end of the valve stem, and a coiled spring surrounding the valve stem between the washer and the valve stem head.

2. In a valve of the class described, a valve body, opposed internal valve and packing seats intermediate the ends of the valve body, opposed ports in the valve seat wall portion of the valve body, a valve member acting against the valve seat, means to prevent rotation of the valve member, a valve stem detachably connected at one end with one end of the valve member, a packing surrounding a portion of the valve stem and acting against the packing seat, a washer mounted on the valve stem acting against the packing, a head having a screw driver slot on the opposite end of the valve stem, a portion of the head being slidably mounted in the valve body and the remainder thereof projecting beyond its respective end of the valve body.

3. A marking ink control valve for fountain marking brushes comprising a cylindrical valve body adapted to be press fitted into a bore intersecting an ink passage leading from an ink reservoir to a marking brush, an external flange at the outer edge of the valve body, a conical valve seat formed within the valve body adjacent one end thereof having opposed ink inlet and ink outlet ports in the side wall thereof communi-

cating with the ink passage, a correspondingly shaped valve member engaging the valve seat to simultaneously close the ink inlet and outlet and adapted when disengaged from the valve seat to simultaneously and progressively open the ink inlet and outlet, a pin and recess connection between the valve member and the free end portion of the wall of the valve body adjacent the valve seat to prevent rotation of the valve member relative to the valve body and to allow limited longitudinal sliding movement of the valve member from its seated position, a conical packing seat in the valve body closely adjacent the small end of the conical valve seat and opposed thereto, a correspondingly shaped molded packing member having a central opening engaging the packing seat, a valve stem slidably mounted in and passing through the packing opening and having screw-threaded connection at its inner end with the inner end of the valve member, a head integral with the outer end of the valve stem having a screw driver slot in the outer face thereof, said head having a sliding fit within the outer end of the cylindrical valve body and normally projecting beyond the flanged end thereof, a 15 washer mounted on the valve stem and engaging the face of larger diameter of the conical packing member, a coiled spring disposed between the

washer and the valve stem head and encircling the valve stem to urge the valve member into its seated position to close the ink inlet and ink outlet, and said valve member being adapted to be unseated by finger pressure on the valve stem head to progressively and simultaneously open the ink inlet and ink outlet in the side wall of the valve seat.
